(57) **CLAIM**

The ornamental design for a storage rack, as shown and described.

DESCRIPTION

FIG. 1 is a perspective view of the storage rack showing my new design;

FIG. 2 is a perspective view thereof from another angle;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 1; and,

FIG. 11 is a partial enlarged view of portion 11 in FIG. 2. The dash broken lines depict portions of the storage rack that form no part of the claimed design. The long dash short dash broken lines depict the boundaries of the detail views and form no part of the claimed design.

1 Claim, 11 Drawing Sheets
